UNITED STATES PATENT OFFICE

ELMER G. GARTIN, OF CLAREMONT, NEW HAMPSHIRE, ASSIGNOR TO SULLIVAN MACHINERY COMPANY, A CORPORATION OF MASSACHUSETTS

DRILLING MECHANISM

Original application filed October 27, 1924, Serial No. 746,242. Divided and this application filed February 23, 1928. Serial No. 256,277.

My invention relates to drilling mechanisms and particularly to hole cleansing means therefor. This application is a division of my copending application Ser. No. 5 746,242 filed Oct. 27, 1924.

An object of my invention is to provide an improved drilling mechanism. Another object is to provide improved hole cleansing means for such a mechanism. Still another 10 object is to provide improved controlling means for the fluid distribution valve of a pressure fluid actuated drilling mechanism to hold the distribution valve in one position to direct a flow of pressure fluid to only the 15 forward end of the motor so as to permit a supply of live pressure fluid to flow to the hollow drill steel to cleanse the hole. A further object is to provide improved pressure fluid operated mechanism for controlling the 20 distribution valve of a drilling mechanism to effect a hole blowing operation. These and other objects and advantages of my invention will hereinafter more fully appear.

In the accompanying drawing I have 25 shown for purposes of illustration one form which my invention may assume in practice.

In the drawing,—

Fig. 1 is a side elevation of a drilling mechanism in which my improved valve controlling and hole cleansing means is embodied, the view being shown partially in 30 central longitudinal section.

Fig. 2 is an end elevational view of the mechanism shown in Fig. 1.

Fig. 3 is a developed longitudinal section 35 taken substantially on line 3—3 of Fig. 2.

In the illustrative form of my invention there is shown a drilling mechanism generally designated 1 comprising a cylinder 2 having a bore 3 in which a hammer piston 4 is reciprocable. The hammer piston 4 is provided with a forwardly projecting striking bar 5 adapted to actuate a hollow drill steel 6 carried by the forward end of the drilling 40 mechanism in a usual manner. The forward end of the cylinder 2 is in communication at the end of every rearward stroke with the bore of the drill steel 6 by way of the usual drill steel rotation flutes 7 in the striking bar 45 of the piston. The upper surface of the cyl-

inder 2 has a valve chest 8 formed integral therewith having a longitudinally extending bore 9 in which is mounted a pair of interchangeable sleeves 10 and 11. The sleeves 10 and 11 are each provided with stepped bores 55 12 and 13, the bores 12 having their outer ends closed by usual vented buffer plugs 14 and 15. The sleeves 10 and 11 and the buffer plugs are held in operative assembled relation by means of transverse springs 16 and co-operating side rods 17. A fluid distribution valve 18, herein of the well known three spool differential type, is disposed within bores 12 and 13 and is adapted alternately to control the supply of pressure fluid to the drilling 60 motor from the supply passage 19 through the distribution passages 20 and 21 communicating with the opposite ends of the cylinder and alternately to control the exhaust from the opposite ends of the cylinder to the passages 65 20 and 21 by means of passages 22 and 23 communicating with the atmosphere. The usual valve throwing passages 24 and 25 communicate at longitudinally spaced points with the cylinder bore 3 and with the bores 12 at the 70 opposite ends of valve 18 by means of passages 26 and 27 formed in the valve sleeves respectively and passages 28 and 29 formed in the buffer plugs. The throttle valve indicated at 30 which may be of any usual form 75 controls the flow of pressure fluid from a supply connection 31 through passages not shown to the supply passage 19 formed in the valve chest in the usual manner.

In my improved construction it will here 80 be observed that the forward buffer plug 15 is provided with a longitudinally extending bore 32 in which a suitable piston 33 is disposed, the diameter of the piston 33 being greater than that of the spools of the valve 85 18. The piston 33 is provided with a longitudinally rearwardly extending stem 34 adapted to engage the forward end of the valve 18. A reduced bore 35 is formed in the buffer 15 in which a spring 36 is disposed normally tending to hold the piston 33 in its extreme forward inoperative position against the inner surface of a plug 37 which closes the forward end of the bore 32. The rear end of 90 the bore 32 is vented to the atmosphere by 95 100

means of a small port 38 (see Fig. 3). As illustrated, the rear buffer plug 14 is provided with a longitudinally extending port 39 which communicates with the bore 12 at the rear end of the valve 18 and with a laterally disposed bore 40 respectively, which is threadedly engaged, as at 41, by a valve casing 42. The valve casing 42 is provided with a longitudinally extending portion 43 in which a longitudinal bore 44 is formed and the portion 43 is secured at 45, herein by brazing, to a pipe connection 46 communicating with a radially extending port 47 which, in turn, communicates with the forward end of the bore 32 formed in the forward buffer plug 15. A cylindrical valve 48 is slidable in the bore 44 and this valve is provided with a stem 49 and an operating member or push button 50 located adjacent the throttle valve 30. A spring 51 is disposed between the valve casing 42 and the push button 50 and this spring normally tends to hold the valve 48 in its extreme rearward inoperative position. The valve 48 is provided with a passage 52 which is adapted to connect the bore 40 formed in the plug 14 with the forward end of the bore 44 which communicates with the bore 32. The bore 44 is provided with a laterally extending vent port 53 which is adapted to connect the forward end of the bore 32 with the atmosphere when the valve 48 is in its inoperative position. It will herein be noted that the stem 34 of the piston 33 is flattened or cut away at 54 to vent the end of the valve, in the usual manner, to the atmosphere through the bores 35 and 32 and the vent passage 38.

In the operation of this form of my improved valve controlling and hole cleansing means it will herein be noted that when it is desired to cleanse the hole the operator manipulates the push button 50, moving the valve 48 to the right, as indicated in Fig. 3, opening communication between the bore 12 at the rear end of the valve 18, which bore communicates with the cylinder bore 3 by means of the throwing passage 24, and with the forward end of the bore 32 by means of the pipe connection 46, thus causing the piston 33 to be moved to the left, the stem 34 engaging the forward end of the valve at this time, consequently causing the valve 18 to be shifted rearwardly and held in its extreme rearward position against the rear buffer plug 14, see Fig. 3. This causes the pressure fluid to flow from the supply passage 19 past the forward surface of the central spool of the valve and through the passage 21 communicating with the forward end of the cylinder bore. The pressure fluid acting on the rear end of the piston 4 is exhausted to atmosphere through the passage 20 and the passage 22 at this time. This causes the pressure fluid within the forward end of the cylinder bore to hold the piston 4 in its ex-

treme rearward position and also causes pressure fluid to flow from the forward end of the motor by way of the usual drill steel rotation flutes 7 formed in the striking bar 5 through the hollow drill steel to cleanse the hole. When the push button 50 is released the pressure fluid in the forward end of the bore 32 is vented to atmosphere by way of the vent port 53 communicating with the bore 44 in the valve casing 42, consequently causing the spring 36 to force the piston 33 and the stem 34 forwardly to its inoperative position, the valve 18 again resuming its normal fluid distributing operation at this time.

As a result of my improvement it will herein be noted that improved valve controlling and hole cleansing means is provided wherein the valve may be held in inoperative position and the flow of pressure fluid directed through the forward end of the motor through the hollow drill steel to cleanse the hole. It will further be noted that improved pressure fluid actuated valve controlling and hole cleansing means is provided which is of an exceedingly simple and compact character and which may be applied to a drilling mechanism of standard form with a minimum of change and expense.

While I have in this application specifically described one form which my invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a fluid actuated rock drill, the combination with a tool actuating motor including a cylinder and a hammer piston reciprocable therein, fluid distribution means for effecting reciprocation of said piston including a valve chest, a fluid actuated fluid distributing valve therein controlling fluid distribution for opposite ends of said cylinder bore and means for conducting pressure fluid from said cylinder to said valve chest to effect throwing of said valve and including a valve throwing passage leading from one end of said valve chest to said cylinder adjacent its forward end, a hollow tool adapted to be actuated by said piston, and means for establishing communication between the forward end of said cylinder and the bore in said tool when the piston is held in its rearward position, of a hole blowing device comprising pressure fluid operated means relative to which said fluid distributing valve is movable during its normal operation for positively shifting said valve against the resisting throwing pressure and holding said valve in one position to effect a hole blowing operation by continuous supply of pressure fluid to the forward end of said cylinder, and

means under manual control for admitting pressure fluid from said throwing passage to said pressure fluid operated means for effecting a hole blowing operation.

2. In a fluid actuated rock drill, the combination with a tool actuating motor including a cylinder having a bore and a piston reciprocable therein, fluid distribution means for effecting reciprocation of said piston including a valve chest, a fluid actuated fluid distributing valve therein for controlling supply and exhaust of motive fluid to and from opposite ends of said cylinder bore and means for conducting pressure fluid from said cylinder bore to said valve chest to effect throwing of said valve including a throwing passage leading from one end of said valve chest to the forward end of said cylinder, a hollow tool actuated by said piston, and means for establishing communication between the forward end of said cylinder and the bore in said tool when said piston is in the rear end of said cylinder, of a hole blowing device including a pressure fluid actuated element relative to which said valve is movable during its normal operation and adapted upon the application of pressure to shift said valve against the resisting throwing pressure and hold said valve immovable in position to cause continuous supply of pressure fluid to the forward end of the cylinder for effecting a hole blowing operation, a conduit leading from said end of the valve chest to said fluid actuated element for supplying pressure fluid to said element from said throwing passage, and a manually controlled valve for controlling flow of fluid through said conduit.

3. In a fluid actuated rock drill, the combination as specified in claim 2 wherein said valve comprises a spring pressed plunger element slidably mounted in said conduit adjacent the rear end of said valve chest, means for permitting flow of pressure fluid through said conduit to said element when said valve is depressed, and means for exhausting said fluid actuated element upon release of said plunger valve.

4. In a fluid actuated rock drill, the combination with a tool actuating motor including a cylinder having a bore and a piston reciprocable therein, fluid distribution means for effecting reciprocation of said piston including a valve chest having a valve chamber, a fluid actuated fluid distributing valve in said valve chamber for controlling supply and exhaust of motive fluid to and from opposite ends of said cylinder bore and means for conducting pressure fluid from said cylinder bore to said valve chamber to effect throwing of said valve including a throwing passage leading from said valve chamber to said cylinder, and a hollow tool actuated by said piston, said motor having associated therewith means for establishing communi-

cation between the forward end of said cylinder and the bore in said tool when said piston is in the rear end of said cylinder, of a hole blowing device including a pressure fluid actuated element relative to which said valve is movable during its normal operation and arranged upon application of pressure thereto to shift said valve against the resisting throwing pressure and hold said valve immovable in position to cause a continuous supply of pressure fluid to the forward end of the cylinder for effecting a hole blowing operation, a cylinder in which said element is contained, a conduit separate from said fluid distribution means leading from said valve chamber to said last mentioned cylinder for supplying pressure fluid to said last mentioned cylinder to effect actuation of said element, and a manually controlled valve for controlling flow of fluid through said conduit.

5. In a fluid actuated rock drilling mechanism, the combination with a hollow tool and a tool actuating motor therefor including a cylinder having a bore with a piston reciprocable therein, fluid distribution means for effecting reciprocation of said piston including a valve chest, a fluid actuated distributing valve therein, and means for effecting opposite movements of said valve including throwing passages extending from points in said cylinder bore at opposite sides of the longitudinal center of the latter to opposite ends of said valve chest, and means operative when said piston is in its rear-most position for connecting the forward end of the cylinder bore with the hollow tool, of a hole blowing device comprising a passage leading from the end of the valve chest to which pressure is admitted to move said distributing valve to admit to the rear end of said cylinder, a valve controlling said last mentioned passage, and means having a surface of greater effective area than the end of said valve in the last mentioned end of the valve chest and arranged to be subjected to pressure admitted through said last mentioned passage, for holding said valve in position to admit to the forward end of the cylinder.

In testimony whereof I affix my signature.
ELMER G. GARTIN.
